UNITED STATES PATENT OFFICE.

ANSEL M. BAUGH, OF OMAHA, NEBRASKA.

DESIGN FOR A VULCANIZER.

43,214.

Specification for Design.

Patented Nov. 5, 1912.

Application filed August 22, 1912. Serial No. 716,543. Term of patent 7 years.

To all whom it may concern:

Be it known that I, ANSEL M. BAUGH, a citizen of the United States, residing at Omaha, in the county of Douglas and State of Nebraska, have invented a new, original, and ornamental Design for a Vulcanizer, of which the following is a specification, reference being had to the accompanying drawing, forming a part thereof.

Figure 1 is a front view of a vulcanizer, showing my new design. Fig. 2 is a side

or end view of the vulcanizer. Fig. 3 is a plan view of the same.

I claim:

The ornamental design for a vulcanizer, as shown.

In testimony whereof I have affixed my signature in presence of two witnesses.

ANSEL M. BAUGH.
